Application January 6, 1950, Serial No. 137,056

25 Claims. (Cl. 166—11)

1

The present invention relates to well packers, and more particularly to packers useful in subjecting well formations to fluid pressures that might be of a comparatively high order.

Well formations may be subjected to comparatively high pressures, which may be in excess of 8,000 p. s. i. As an example, the formation at a predetermined depth in the well bore is to be fractured hydraulically by pumping a particular fluid medium into it under high pressures. Difficulties have heretofore been encountered in providing subsurface equipment that can be run in the well casing and be capable of withstanding and delivering such high pressures to the formation. This is especially true of well packers of the retrievable type which are to straddle the perforations in the well casing. Such straddle tools should be capable of localizing the hydraulic pressure to a comparatively small region at any one time, and, if the longitudinal extent of perforations in the casing is large, to pressurize progressively the formation from the bottom of the casing perforations upwardly.

Accordingly, an object of the invention is to provide a well packer mechanism capable of straddling casing and similar perforations and of directing and localizing comparatively high fluid pressures on the formation behind the casing.

Another object of the invention is to provide a well packer mechanism capable of straddling some of an extended length of perforations in the well casing, and of directing fluid pressure through the straddled perforations, without subjecting the casing itself to such fluid pressure. More particularly, the casing above the perforations is not subjected to the fluid pressure.

Another object of the invention is to provide a well packer mechanism embodying retractible and expansible packing elements adapted to be located on opposite sides of casing perforations, and capable of remaining in packed-off condition against the well casing while being subjected to very high fluid pressures.

A further object of the invention is to provide a well packer mechanism embodying packing elements that can be selectively expanded or retracted against and from a well casing, to enable the packer to be set, as desired, on opposite sides of casing perforations. Because of this capability, the mechanism can be utilized in progressively pressurizing the formation in step-by-step fashion from the bottom of an extended length of the casing perforations in an upward direction.

Still another object of the invention is to pro-

2

vide a well packer embodying a normally retracted packing which is outwardly expandable against the well casing by compressing the packing in the longitudinal direction, and which is held in leakproof relation against the casing despite longitudinal movement of well packer parts which would ordinarily tend to loosen the packing.

This invention possesses many other advantages, and has other objects which may be made more clearly apparent from a consideration of several forms in which it may be embodied. Such forms are shown in the drawings accompanying and forming part of the present specification. These forms will now be described in detail, illustrating the general principles of the invention; but it is to be understood that such detailed description is not to be taken in a limiting sense, since the scope of the invention is best defined by the appended claims.

Referring to the drawings:

Figures 1, 1a and 1b together constitute a longitudinal section through a well packer apparatus disposed in a well casing, Fig. 1a constituting a lower continuation of Fig. 1, and Fig. 1b constituting a lower continuation of Fig. 1a;

Figs. 2, 2a and 2b are views similar to Figs. 1, 1a and 1b, respectively, disclosing the packer anchored in packed-off condition against the well casing;

Fig. 3 is a side elevation, on a reduced scale, illustrating the well packer apparatus in retracted position within a well casing;

Fig. 4 is an enlarged longitudinal section of the lowermost packing structure in packed-off condition;

Fig. 5 is a cross-section taken along the line 5—5 on Fig. 1;

Fig. 6 is a longitudinal section through a modified form of the lowermost portion of the tool.

The well packer apparatus A disclosed in the drawings is particularly designed for forcing fluids under high pressures through perforations P in a well casing B, in order to subject the formation behind the perforated region of the well casing to such pressures, and thereby effect its fracture. The equipment can be used for forcing fluid under pressure through an extended length of perforations P in the well casing by selectively setting and releasing the packer A with respect to the casing B. Thus, the packer may be caused to localize a small zone in the casing at the bottom of the perforations and then force fluids under pressure through such per-

forations. The tool may then be released and moved to a higher elevation, where it can be set, and fluid under pressure forced outwardly through the next higher perforations. Progressive setting, pressuring and release of the packer may take place in upward sequence along the perforations, until the entire length of formation opposite the perforations P has been subjected to pressure.

During the above operation, the casing above its perforated portion does not have pressure imposed upon it. As a result, bursting of the casing B under high pressures is avoided.

The apparatus can be run in the well casing on the lower end of a tubular string (not shown) extending to the top of the well bore. The central mandrel or body 10 of the tool is secured to this tubular string. This mandrel or body is tubular, to provide a passage extending through it, that is communicable with the tubing string.

The packer body 10 includes an upper portion 11 attached to the tubular string, the lower end of this upper portion being threaded, by means of a right-hand threaded connection, into a safety collar 12, which is, in turn, threaded onto a lower mandrel or body portion 13 by means of a left-hand threaded connection 14. The lower mandrel 13, in turn, is threaded into an intermediate coupling 15 that is threaded onto the upper end of a mandrel or body extension 16 having its lower end threaded into the box portion 17 of the lowermost packer body 18. All of the threaded connections are preferably right-hand ones except the safety joint 14, which is left-hand, to enable the upper body section 11 and safety collar to be unscrewed from the lower mandrel 13 whenever difficulty is encountered in retrieving the tool from the well casing, as explained below.

The well packer A is adapted to be anchored to the casing B against upward movement. It is provided with longitudinally spaced packing structures 19, 20, 21, that are normally in retracted position, but which are adapted to be expanded outwardly against the well casing B, as on opposite sides of the casing perforations P, to establish a localized pressure zone or region in the well casing through which fluid under pressure may be forced, for passage through the perforations P and into the formation.

In order to anchor the tool in the well casing, its upper portion is provided with an anchoring device of the type disclosed in United States Patent No. 2,368,401. This device includes an expander member 22 slidable relatively along the upper mandrel or body 11, and having tapered surfaces 23 cooperable with companion tapered slips 24. These slips have wickers or teeth 25 facing in an upward direction, and designed to dig into the casing wall, for the purpose of preventing upward movement of the well packer therewithin.

The slips 24 are movable jointly along the expander 22, to and from an expanded position against the casing wall, by pin-connecting them to the lower ends of links 26. The upper ends of the links have transversely extending pins 27 receivable within a coupling or slip sleeve 28, that is connected, by means of a swivel 29, to a friction drag and lock device 30. This latter device includes a lower collar 31 slidable along the upper mandrel 11, with a lower annular nut 32 threaded into the collar, and having an external flange 33 received within an inner circular groove 34 in a two-part ring 35, the two parts

of the ring being suitably held together by an encompassing sleeve 36. Also received within the ring 35 below the annular nut flange 33 is an external flange 37 extending from the upper end of the coupling sleeve 28.

The lower ends of a plurality of outwardly bowed springs 38 are suitably secured to the lower drag collar 31, the upper ends of such springs being secured to an upper drag collar 39 slidable relatively along the upper mandrel 11.

The springs 38 frictionally engage the casing B, and tend to resist longitudinal movement of the slips 24 therewithin in both directions. When the slips are to be set, the mandrel 10 is moved upwardly, which moves the slip expander 22 upwardly (through parts to be described hereinafter) within the slips 24, urging the latter radially outward against the casing B, because of the cooperating tapered surfaces 23, 23a on the expander and the slips. The slips 24 cannot move longitudinally, when unlocked from the mandrel 10, because of the resistance to movement offered by the springs 38 against the casing B.

Lowering of the mandrel 10 will lower the slip expander 22 with respect to the slips 24, and enable the latter to be retracted from the well casing. Here again, the friction springs 38 resist longitudinal movement of the slips, and enable this action to occur.

In order to permit the mandrel 10 to be moved upwardly without shifting the slips 24 against the casing B, a lock device is provided between the mandrel and the lower drag collar 31. This lock device may be of the type described in the above referred to patent. It includes a split ratchet ring 40 having an external surface 41 tapering in an upward direction for engagement with a companion internal surface 42 in the lower drag collar. Ratchet teeth 43 facing in a downward direction are provided in the ring 40 for cooperation with companion upwardly facing ratchet teeth 44 on the periphery of the mandrel 10.

It is apparent that any tendency for the mandrel 10 to move upwardly causes its teeth 44 to engage the ratchet teeth 43 in the split ring 40, and, in view of the wedging engagement of the ring in the collar 31, couples the latter to the mandrel 10, which also couples the slips 24 to the mandrel and prevents relative longitudinal movement between them. Of course, the mandrel can move freely in a downward direction within the ratchet ring 40, in view of the slope of the peripheral faces on the ratchet teeth 44, 43.

The ratchet lock ring 40 may be rendered ineffective by moving the mandrel 10 angularly, which will expand the ring 40 away from the mandrel teeth 44, allowing the mandrel to move upwardly within the lock ring and the lower drag collar 31, as explained in the above United States Patent No. 2,368,401.

The slip expander 22 has a depending extension 45 threaded on its lower end, which is provided with perforations or longitudinal slots 46. This extension, in turn, is threaded onto an upper abutment 47 disposed immediately below the safety collar 12. This abutment 47 is spaced outwardly of the lower mandrel or body 13 to provide an annular space 48 in which an upper packing compression sleeve 49 of the upper packing structure 19 may move. This compression sleeve 49 is slidable relatively along the lower mandrel 13 and has an outwardly directed flange

50 integral therewith. The flange is provided with a gauge ring 51 threaded on it, which actually forms a lateral continuation of the flange 50 itself. The flange and gauge ring together form a lower support for a packing sleeve 52, of natural or synthetic rubber, which encompasses the compression sleeve 49. The upper end of the packing sleeve 52 engages the upper abutment 47. When the compression sleeve 49 is moved in an upward direction toward the upper abutment 47, the upper packing sleeve 52 is foreshortened and compressed, being expanded outwardly against the casing wall.

A skirt 53 depends from the flange portion 50 of the upper compression sleeve 49, and is threaded onto a lower compression sleeve 54 that may have perforations 55 near its upper end. This lower compression sleeve 54 extends downwardly along the lower mandrel or body 13 and is threaded into a coupling collar 56 adjacent the intermediate coupling 15 between the lower mandrel 13 and the mandrel extension 16. A compression sleeve extension 57 is also threaded into the coupling collar 56, and depends along the mandrel extension 16 to substantially the same lower point as the latter, terminating adjacent the lowermost body box 17, where it is threaded into a lower coupling 58 fitting loosely around an abutment member 59 laterally spaced from the lowermost body 18, to form an annular space 60 in which the upper end of another packing compression sleeve 61 is movable. This compression sleeve 61 is slideable longitudinally along the lowermost body member 18. The abutment member 59 may originally engage a shoulder 62 on the box portion 17 of the lowermost body 18, and it may also be provided with perforations 63 to prevent fluid from being entrapped within the annular clearance space 60 between the abutment and the lowermost body.

The abutment may have a gauge ring 64 threaded on it to increase its maximum external diameter. An intermediate packing sleeve 65 of rubber or similar material is disposed around the compression sleeve 61, with its upper end engageable with the abutment 59 and gauge ring 64, and its lower end resting upon a flange 66, integral with the compression sleeve 61, and on which a gauge ring 67 may also be threadedly mounted. The parts 59, 61, 64, 65, 66, 67 together constitute the intermediate packing structure 20.

The flange 66 rests upon a spacer sleeve 68 having perforations 69, the lower end of which bears against the flange portion 70 of a lower packing compression sleeve 71 slideable relatively along the lowermost body or mandrel portion 18. This compression sleeve 71 is movable within the annular clearance space 72 formed between the body 18 and an adjusting nut and guide 73 threaded on the lower end of the mandrel. This adjusting nut and guide also has perforations 74 through its wall to permit fluid to flow in and out of the annular space 72. It also possesses a gauge ring 75 which increases the effective outside diameter of the adjusting nut or abutment 73. The lower end of a lowermost rubber packing sleeve 76 rests upon the lowermost abutment 73 and gauge ring 75, the packing sleeve 76 encompassing the compression sleeve 71, with its upper end being disposed adjacent the flange 70, on which a gauge ring 77 is threaded. The parts 70-77 together constitute the lower packing structure 21.

The tubular mandrel or body sections 11, 13, 16,

18 have a passage 78 therein which may terminate in the lowermost mandrel portion 18. Leakage from the passage 78 is prevented by providing suitable thread seals 79 at each threaded connection between the various mandrel elements. The mandrel passage 78 communicates with the annular space 80 within the lower spacer sleeve 68 through a plurality of mandrel ports 81, fluid within the mandrel being capable of passing outwardly through the mandrel ports 81 and through the ports or perforations 69 in the spacer sleeve into the region 82 between the intermediate and lower packing structures 20, 21.

In order to prevent leakage of this fluid through the interior of the packing sleeves 65, 76, the compression sleeves 61, 71, on which the latter are mounted, are provided with suitable side seals 83, such as rubber O rings, disposed in suitable grooves 84 and slidably and sealingly engaging the exterior of the lowermost mandrel member 18. When the two lower elastic packing sleeves 65, 76 are foreshortened and compressed outwardly against the wall of the casing B, they form the localized zone 82, into which fluid from the mandrel can be pumped under very high pressure, for outward passage through the casing perforations P and into the formation.

It is also desired that fluid be prevented from passing along the exterior of the mandrel within the uppermost elastic packing structure 19. For this reason, the upper compression sleeve 49 may be provided with a suitable side seal 85 sealingly engageable with the exterior of the mandrel 13. When the upper packing 52 has been foreshortened and compressed against the well casing, fluid is prevented from passing around this packing.

It is preferred to employ the threaded and replaceable gauge rings 51, 64, 67, 71, 75 on the abutment and compression sleeve members, so as to hold the clearance space between the gauge rings and the casing wall to as low a value as is practical, thereby minimizing the opportunity for cold flowing of the rubber packing material through such clearance space when the packing elements are subjected to high pressures. A suitable outside diameter gauge ring is selected, depending upon the inside diameter of the casing string in which the tool is to be anchored in packed-off condition.

The apparatus is assembled and is run in the well casing with the slips 24 and the various packing sleeves 52, 65, 76 in retracted positions, and with the parts occupying the relationship illustrated in Figs. 1, 1a and 1b, and Fig. 3. During lowering through the well casing B, the friction drag springs 38 tend to resist downward movement of the slips 24. However, the mandrel 10 may ratchet freely in a downward direction through the lock ring 40, its downward movement being limited by engagement of the safety collar 12 with the upper abutment 47. Since this upper abutment is connected to the expander extension 45, the downward movement and force is transmitted to the slip expander 22, urging the latter downwardly of the slips 24 and holding the latter in an inward position, in view of the dove-tail connection 86 between the expander 22 and slips 24. The slips 24, through their connected links 26 and swivel connection 29, pull downwardly on the lower drag collar 31, and slide the friction springs 38 along the casing wall.

The adjusting nut and guide 73 also moves downwardly with the mandrel 10, since it is attached to it. The various packing members and compression sleeves, in effect, float between the

uppermost abutment 47 and the adjusting nut guide 73, since there is nothing tending to compress and foreshorten the sleeves 52, 65, 76 during downward movement of the tool. That is, all of the packing rubber elements remain in their normal, inherently retracted positions during lowering of the tool A in the well casing B.

In the event that the well casing B has an extended length of perforations P, it is desired to locate the lower packing sleeves 65, 76 on opposite sides of the lowermost group of perforations, so as to localize the application of pressure through these perforations. The uppermost packing sleeve 52 is to be expanded against an imperforate casing portion R above the perforations P for the purpose of preventing the pressure from being imposed on the interior of the casing B.

The spacer sleeve 68 between the two lower packing structures 20, 21 is of such length as to subtend a predetermined length of perforations P. The distance between the intermediate packing sleeve 65 and the uppermost packing sleeve 52 should be selected so that the uppermost packing sleeve will be packed off against the imperforate casing section R. This necessary distance is obtainable merely by coupling mandrel extension members 16 to one another of the desired length between the intermediate coupling 15 and the threaded box 17 of the lowermost body portion 18. Similarly, the proper number or sections of compression sleeve extensions 57 can be coupled to one another between the coupling collar 56 and the coupling 58 which bears upon the abutment 59. Of course, the combined mandrel extension 16 used and compression sleeve extension 57 used should be of substantially equal lengths.

When the point is reached in the well casing B at which the tool A is to be set, the running-in string and tubular mandrel 10 are moved angularly to the right, to release the lock ring 40 from the mandrel, as described in the above patent. The mandrel 10 is then moved upwardly, the adjusting nut and guide 73, the lower packing structure 21, spacer sleeve 68, intermediate packing structure 20, compression sleeve extension 57, compression sleeve 54, upper packing structure 19, expander extension 45 and expander 22 moving upwardly with the mandrel 10 with respect to the slips 24, which are prevented from moving upwardly by the frictional engagement of the drag springs 38 against the casing B. The rubber packing sleeves 52, 65, 76 are sufficiently hard as to transmit the upward movement without deformation. For that matter, as explained below, the uppermost packing sleeve 52 is softer than the intermediate packing sleeve 65, which, in turn, is softer than the lowermost packing sleeve 76, so that the uppermost packing sleeve 52 can be first compressed, then the intermediate packing sleeve 65, then the lower packing sleeve 76, as upward movement of the mandrel 10 continues.

When the mandrel 10 is moved upwardly, the slip expander 22 is moved upwardly within the slips 24, urging the latter in a radial outward direction and into anchoring engagement with the wall of the casing B. When engaged with the casing, the slips 24 prevent the slip expander 22, expander extension 45 and the upper abutment 47 from moving any further. Accordingly, a continuation of the upward movement of the mandrel 10 urges all of the parts around the mandrel and below the upper abutment 47 in an upward

direction, the upper compression sleeve 49 moving within the upper abutment 47, causing its flange 50 to foreshorten the uppermost packing sleeve 52, compressing it and expanding it laterally 5 against the wall of the casing B. During such upward movement, the safety collar 12 is moved upwardly away from the upper abutment 47 (see Fig. 2a).

Since the upper packing sleeve 52 has been 10 firmly compressed against the casing B, it prevents further upward movement of its compression sleeve 49 and the compression sleeve 54 and compression sleeve extension 57 secured to it, as well as the abutment 59 engaging the coupling 15 15 on the compression sleeve extension 57. Accordingly, continuation of the upward strain and movement of the mandrel 10 shifts the intermediate compression sleeve 61 within the abutment 59, causing its flange 66 to foreshorten the intermediate packing sleeve 65 and expand it outwardly against the casing B. During this upward movement, the threaded box 17 on the lowermost body portion 18 moves upwardly away from the abutment 59. When the intermediate sleeve 65 25 has been firmly compressed against the casing, it prevents further upward movement of its compression sleeve 61, the spacer sleeve 68 and the lowermost compression sleeve 71. Accordingly, as upward movement of the mandrel 10 continues, 30 the adjusting nut 73 is moved upwardly along the lowermost compression sleeve 71, foreshortening the lowermost packing 76 and expanding it outwardly against the wall of the well casing B.

An adequate upward strain can be taken on 35 the mandrel 10 to insure that the slips 24 have been embedded into the wall of the casing, and that all of the packing sleeves 52, 65, 76 have been firmly expanded against the casing wall. The uppermost packing sleeve 52 is packed-off 40 against an imperforate portion R of the casing above the uppermost perforations P, whereas the lower two rubber packing sleeves 65, 76 are packed-off on opposite sides of the lower perforations to form the localized zone 82 therein.

Fluid under pressure may now be pumped 45 downwardly through the tubing string and through the mandrel passage 78 for outward passage through the mandrel ports 81 and spacer sleeve ports 89 into the localized zone 82 between the lower packing structures 20, 21, this fluid under pressure passing outwardly through the lowermost perforations P and into the formation. If a sufficiently high pressure is imposed, the formation will be fractured.

This fracturing can be accomplished by pumping 50 a suitable fluid, such as oil, into the formation. After the fracturing has been accomplished, sand laden oil may be pumped into the formation, in order that the sand particles may serve 55 as props in the fractured regions of the formation, holding the fractures or fissures open.

Inasmuch as perforations P are present above the intermediate packing sleeve 65, the pressure 60 can pass outwardly around the exterior of the casing B, and then back into the casing through its perforations above the intermediate packing sleeve. Despite this occurrence, the uppermost packing 52 is still expanded outwardly against the casing portion R above the perforations P, to prevent the annulus between the casing and the tubular running-in string from being subjected to pressures, which might be of such a high degree as to burst the casing. The pressure is localized at the perforated casing region, there being no bursting strains placed on the casing

at all, since the perforations P allow the pressure internally and externally of the casing to be equalized.

After the necessary high pressures have been imposed on the formation and the high pressure fluid displaced into the formation through the lowermost set of perforations, the running-in string and mandrel 10 may be lowered to enable the packings 52, 65, 76 to retract and to force the slips 24 to retracted position. The lock ring 40 may be allowed to engage the ratchet teeth 44 on the mandrel 10, in order that the tubing string may be elevated the required distance until the two lower packing assemblies 20, 21 are disposed opposite the next higher group of perforations. The tool may again be anchored in packed-off condition, in the manner described above, to allow fluid under pressure to be forced through the next group of straddled perforations P. The tool may be released and elevated to the next higher position, where it can again be anchored in packed-off condition, this cycle of operations being continued until all of the perforations P have been straddled and the desired fluent mediums pumped through the perforations and into the formation. When the full operation has been completed, the parts of the tools may be shifted to retracted positions and the entire apparatus removed from the well bore.

When the tool is subjected to very high pressures, as, for example, in excess of 8,000 p. s. i., such pressures tend to elongate the tubular mandrel 10. If it were not for the particular design of the tool disclosed, such elongation might tend to move the lower adjusting nut and guide 73 in a downward direction, and if the compression sleeve 71 and its flange 70 and gauge ring 77 did not follow up movement of the adjusting nut and guide 73, and lowermost packing 76 might be released. Such release does not occur in the present tool, for reasons that now will be pointed out.

Inasmuch as the upward movement of the mandrel 10 in setting the tool in packed-off condition has disposed the collar 12 and threaded box 17 above the several abutments 47, 59, the downward stretching of the tubing string and mandrel 10, under high pressure conditions, can take place, since adequate longitudinal clearance space is present between the collar and box members 12, 17 and the abutments 47, 59. Despite extensive stretching of the tubing string and mandrel 10, the safety collar 12 and box 17 do not move sufficiently to engage the abutments 47, 59, which action, if it could occur, might tend to shift the expander 22 downwardly and release the slips 24 from the casing.

As the mandrel 10 moves downwardly, as a result of the hydraulic stretching force, the lower adjusting nut and guide 73 moves downwardly with it. However, the lowermost packing 76 remains in packed-off condition, since the pressure is acting downwardly on the packing structure 21 over the annular area A between the periphery of the mandrel 10 and the casing wall. The hydraulic pressure acting downwardly in this direction over the area A causes the abutment and compression sleeve 71 to follow up the downward movement of the lower adjusting nut 73 with a greater force than the effective force moving the lower adjusting nut 73 in a downward direction away from the lowermost packing 76. This latter force is acting in an upward direction on the packing over the annular area B between the compression sleeve 71 and the wall of the well casing B. This

annular area B is less than the annular area A by the annular area C of the compression sleeve itself. As a result, there is a differential area C with which the hydraulic pressure in the localized zone 82 can act in a downward direction on the lower packing 76, holding it firmly compressed between the sleeve abutment 70 and the adjusting nut 13, and securely expanded outwardly against the well casing. The packing assembly 21 may move downwardly, if the mandrel 10 moves or stretches downwardly, but it will still remain in packed-off condition under high operating conditions, to maintain the sealed localized zone 82 between the packing assemblies 20, 21.

The tool has been described in connection with the progressive pressuring of an extended length of perforations P in a well casing B. For such use, the three packing assemblies 19, 20, 21 are preferred, in order to locate the uppermost packing assembly 19 above the perforations P and prevent the pressure from being imposed on the well casing itself. In the event that the tool is to be used in connection with a short perforated length of casing, which can be subtended by a pair of packing elements, the intermediate rubber packing 65 can be omitted, its place being taken by a rigid sleeve of the same length as the packing 65 when the latter is in retracted position. The tool would then be set in the well casing with the upper packing 52 disposed above the perforations P, and the lower packing 76 below the perforations, the tool being anchored in packed-off condition through upward movement of the tubular mandrel 10, in essentially the same manner as before.

The left-hand threaded connection 14 is provided between the safety collar 12 and the lower mandrel 13 to enable the slips 24 to be substantially retracted, in the event that they cannot otherwise be freed, as, for example, as a result of sticking or freezing of the lower packing portions against the well casing. When the well packer is set, the tubing string and the mandrel 10 have been rotated to the right, in order to expand the lock ring 40 and allow the mandrel to be elevated as described above. Forcible retraction of the slips 24 can occur by coupling the mandrel 10 to the slips 24 through the lock ring 40. Such coupling action can take place as a result of returning the mandrel 10 to its original position, as by rotating it to the left. This left-hand rotation may produce a tendency to unscrew or loosen one or more of the right-hand threaded joints in the tubing string. To insure that this will not occur, instead of first rotating the tubing string and mandrel 10 to the left, to allow contraction of the lock ring 40, and its coupling to the mandrel 10, the tubing string is first rotated to the right, which will unthread the left-hand safety joint 14. The tubing string joints cannot unscrew, because the tubing string is being rotated to the right while the left-hand threaded connection at the safety joint is being broken. After the safety collar 12 has been completely unscrewed from the lower mandrel 13, substantially all resistance to rotation of the tubing string is removed. The latter may now be rotated to the left, without danger of unthreading any of its right-hand joints, in order to recouple the mandrel 10 to the lock ring 40 and allow the mandrel 10 to be elevated, such elevation pulling the slips 24 upwardly along the expander 22 and inwardly out of engagement from the well casing. When the slips 24 are released, the packings, even though they may not be retracted, will slide

along the casing wall. As a result, the entire tool can be withdrawn from the well bore.

In the event that high pressures are encountered in the well casing B below the expanded lowermost packing 76, which high pressures might tend to release this packing, an equalizing valve structure may be provided in the lower portion of the lowermost body 18 (see Fig. 6). This equalizing valve includes a valve body 100 threaded into the lowermost mandrel section 18, this body having side ports 101 communicating with a central body passage 102, and also having a lower socket 103 in which the lower end of a valve stem 104 is received. This valve stem extends upwardly through the passage 102 in spaced relation to its side wall and terminates in an upper head 105 engageable with a valve seat 106 in the body when the head moves downwardly, to prevent downward flow of fluid through the mandrel passage 18. In view of the high pressures encountered, a metal-to-metal contact is provided between the head 105 and valve seat 106, but, as assurance against leakage between the two, a supplemental seal ring 107 may be clamped between the upper part of the valve body and the mandrel 18, against which the head 105 also seats.

The valve head 105 and its stem 104 are urged in a downward direction by a helical compression spring 108 bearing against the base of the socket 103 and also against a washer 109, which rests upon a suitable nut 110 threaded on the lower end of the valve stem 104. The compression spring 108 normally urges the valve head 105 downwardly to closed position. However, fluid under sufficient pressure may enter the valve body through the ports 101 and annular passage 102, acting upwardly on the head 105 to shift it from its seat 106 to open position.

During normal use of the tool, the valve head 105 remains closed against its seat 106, since the pressure inside of the mandrel 10 is greater than the pressure outside of the tool below the lowermost packing 76. In the event that the pressure below the lowermost packing tends to exceed the internal pressure, this excess pressure will elevate the head 105 from its seat 106 and allow the higher pressure fluid to enter the mandrel 10. This pressure may then leave the mandrel through the mandrel and spacer sleeve ports 81, 69, and is effective for downward action over the lowermost compression sleeve 71 and packing element 76, to hold such packing 76 sealed against the well casing B.

The inventors claim:

1. In a well packer: a tubular body having a port; a packing structure surrounding said body on each side of said port; means engageable with said packing structures to support said structures on opposite sides of said port; each of said packing structures including a sleeve slidable on said body and having a flange, a normally retracted packing on said sleeve having one end engaging said flange, an abutment slidable on said sleeve and engaging the other end of said packing, and means for moving said abutment and flange relatively toward each other to compress each packing and expand it laterally outward.

2. In a well packer adapted to be lowered in a well casing: a tubular body having a port; first and second normally retracted casing engaging packings surrounding said body and disposed on opposite sides of said port, said second packing having an upper end and a lower end; means engageable with the well casing and with said

first packing for resisting movement of said first packing in the casing; abutment means on said body engageable with one of the ends of said second packing, a sleeve within said second packing and slidable on said body and within said abutment means, said sleeve having a flange engaging the other end of said second packing; and means between said packings for transmitting to said first packing the force supplied by said body to said second packing, in order to compress both packings and expand them against the well casing.

3. In a well packer adapted to be lowered in a well casing: a tubular body having a port; upper and lower normally retracted packings surrounding said body and disposed on opposite sides of said port; means engageable with the well casing and with said upper packing for resisting movement of said upper packing in the casing; abutment means on said body engaging the lower end of said lower packing; a sleeve within said lower packing and slidable on said body and within said lower abutment means, said sleeve having a flange engaging the upper end of said lower packing; and means between said packings for transmitting to said upper packing the force supplied by said body to said lower packing, in order to compress both packings and expand them against the well casing.

4. In a well packer adapted to be lowered in a well casing: a tubular body having a port; upper and lower normally retracted packings surrounding said body and disposed on opposite sides of said port; an upper abutment movable relatively of said body and engageable with the upper end of said upper packing; means engaging said abutment and the wall of the well casing to prevent upward movement of said abutment in the casing; a lower abutment mounted on said body and engaging the lower end of said lower packing; and spacer means on said body engaging the lower end of said upper packing and the upper end of said lower packing, in order that upward movement of said body can effect compression of both packings and their outward expansion against the well casing.

5. In a well packer adapted to be lowered in a well casing: a tubular body having a port; upper, intermediate and lower normally retracted packings surrounding said body, said intermediate and lower packings being disposed on opposite sides of said port; means engageable with the well casing and with the upper end of said upper packing for resisting upward movement of said upper packing in the well casing; means on the body engaging the lower end of said lower packing; spacer means on the body between the lower end of said upper packing and the upper end of said intermediate packing; and spacer means on said body between the lower end of said intermediate packing and the upper end of said lower packing; both of said spacer means enabling upward movement of said body to effect compression of said upper, intermediate and lower packings and their expansion against the well casing.

6. In a well packer adapted to be lowered in a well casing: a tubular body having a port; first and second normally retracted casing engaging packings surrounding said body and disposed on opposite sides of said port, each of said packings having an upper end and a lower end; a first sleeve slidable on said body and disposed within said first packing; a second sleeve slidable on said body and disposed within said second packing; a flange on said first sleeve engaging one of the

ends of said first packing; a flange on said second sleeve engaging one of the ends of said second packing; means engageable with said casing and the other end of said first packing, said first sleeve being slidable in said casing engageable means; means on said body engageable with the other end of said second packing, said second sleeve being slidable in said means on said body; and a spacer sleeve on said body located between and engageable with said first and second sleeves.

7. In a well packer adapted to be lowered in a well casing: a tubular body having a port; upper and lower normally retracted casing engaging packings surrounding said body and disposed on opposite sides of said port; an upper sleeve slid-able on said body and disposed within said upper packings; a lower sleeve slidable on said body and disposed within said lower packing; a flange on said upper sleeve engaging the lower end of said upper packing; a flange on said lower sleeve en-gaging the upper end of said lower packing; means engageable with said casing and the upper end of said upper packing for resisting its up-ward movement in the casing, said upper sleeve being slidable in said casing engageable means; means on said body engageable with the lower end of said lower packing, said lower sleeve being slidable in said means on said body; and a spacer sleeve on said body located between and engageable with said upper and lower sleeves.

8. In a well packer adapted to be lowered in a well casing: a tubular body having a port; upper, intermediate and lower normally retracted casing engaging packings surrounding said body, said intermediate and lower packings being disposed on opposite sides of said port; an upper sleeve slidable on said body and disposed within said upper packing; an intermediate sleeve slidable on said body and disposed within said intermediate packing; a lower sleeve slidable on said body and disposed within said lower packing; a flange on said upper sleeve engaging the lower end of said upper packing; a flange on said intermediate sleeve engaging the lower end of said intermediate packing; a flange on said lower sleeve en-gaging the upper end of said lower packing; means engageable with said casing and the upper end of said upper packing to resist its upward movement within the casing, said upper sleeve being slidable in said casing engageable means; means on said body engageable with the lower end of said lower packing, said lower sleeve being slidable in said means on said body; sleeve means on said body extending between and engageable with said upper sleeve and the upper end of said intermediate packing, said intermediate sleeve being slidable in said sleeve means; and a spacer sleeve on said body located between and engageable with said intermediate and lower sleeves.

9. In a well packer adapted to be lowered in a well casing: a body; a sleeve slidable on the exterior of said body in close contacting leakproof relation with respect to said exterior of said body and having a flange; a normally retracted casing-engaging packing on said sleeve, said packing having one end engaging said flange; and an abutment surrounding said body and slidable on said sleeve and engageable with the other end of said packing to expand said packing into engagement with the well casing.

10. In a well packer adapted to be lowered in a well casing: a tubular body having a port; a sleeve slidable on the exterior of said body in close contacting leakproof relation with respect to said exterior of said body and having a flange

to one side of said port, said sleeve having a skirt leading from said flange in a direction away from said port; a normally retracted casing-engaging packing on said skirt having an end engaging said flange; and an abutment surrounding said body and slidable on said skirt and engageable with the other end of said packing to expand said packing into engagement with the well casing.

11. In a well packer adapted to be lowered in a well casing: a tubular body having a port; a sleeve slidable on the exterior of said body below said port in close contacting leakproof relation with respect to said exterior of said body and having a flange, said sleeve having a skirt depending from said flange; a normally retracted casing-engaging packing on said skirt having its upper end engaging said flange; and an abutment on said body slidable on said skirt and engageable with the lower end of said packing to expand said packing into engagement with the well casing.

12. In a well packer adapted to be lowered in a well casing: a tubular body having a port; first and second normally retracted casing engaging packings surrounding said body and disposed on opposite sides of said port, said second packing having an upper end and a lower end; normally retracted slips disposed about said body; ex-pander means engageable with said first packing and coacting with said slips for expanding said slips against the casing to resist movement of said first packing in the casing; abutment means on said body engageable with one of the ends of said second packing; a sleeve within said second packing and slidable on said body and within said abutment means, said sleeve having a flange en-gageable with the other end of said second pack-ing; and means on said body between said packings for transmitting to said first packing the force supplied by said body to said second pack-ing, in order to compress both packings and expand them against the well casing.

13. In a well packer adapted to be lowered in a well casing: a tubular body having a port; upper and lower normally retracted packings surround-ing said body and disposed on opposite sides of said port; normally retracted slips disposed around said body; expander means engageable with said upper packing and coacting with said slips for expanding them against the casing to resist upward movement of said upper packing in the casing; means on said body engageable with the lower packing for urging said lower packing upwardly upon upward movement of said body in the casing; and means on said body between said packings for transmitting to said upper packing the upwardly directed force supplied by said body to said lower packing, in order to compress both packings and expand them against the well casing.

14. In a well packer adapted to be lowered in a well casing: a tubular member having a port; upper and lower normally retracted packings surrounding said body and disposed on opposite sides of said port; an upper abutment movable relatively of said body and engageable with the upper end of said upper packing; normally retracted slips disposed about said body; expander means engageable with said abutment and coacting with said slips for expanding them against the casing to resist upward movement of said upper abut-ment in the casing; a lower abutment mounted on said body and engaging the lower end of said lower packing; and spacer means on said body engaging the lower end of said upper packing and the upper end of said lower packing, in order that

upward movement of said body can effect compression of both packings and their outward expansion against the well casing.

15. In a well packer adapted to be lowered in a well casing: a tubular body having a port; upper, intermediate and lower normally retracted packings surrounding said body, said intermediate and lower packings being disposed on opposite sides of said port; normally retracted slips disposed around said body; expander means engageable with the upper end of said upper packing and coacting with said slips for expanding them against said casing to resist upward movement of said upper packing in the casing; means on the body engaging the lower end of said lower packing; spacer means on the body between the lower end of said upper packing and the upper end of said intermediate packing; and spacer means on said body between the lower end of said intermediate packing and the upper end of said lower packing; both of said spacer means enabling upward movement of said body to effect compression of said upper, intermediate and lower packings and their expansion against the well casing.

16. In a well packer adapted to be lowered in a well casing: a tubular body having a port; upper and lower normally retracted casing engaging packings surrounding said body and disposed on opposite sides of said port; an upper sleeve slideable on said body and disposed within said upper packing; a lower sleeve slideable on said body and disposed within said lower packing; a flange on said upper sleeve engaging the lower end of said upper packing; a flange on said lower sleeve engaging the upper end of said lower packing; normally retracted slips disposed about said body; expander means engageable with the upper end of said upper packing and coacting with said slips for expanding them against the casing to resist movement of said upper packing in the casing; means on said body engageable with the lower end of said lower packing; and a spacer sleeve on said body located between and engageable with said upper and lower sleeves.

17. In a well packer adapted to be lowered in a well casing: a tubular body having a port; upper, intermediate and lower normally retracted casing engaging packings surrounding said body, said intermediate and lower packings being disposed on opposite sides of said port; an upper sleeve slideable on said body and disposed within said upper packing; an intermediate sleeve slideable on said body and disposed within said intermediate packing; a lower sleeve slideable on said body and disposed within said lower packing; a flange on said upper sleeve engaging the lower end of said upper packing; a flange on said intermediate sleeve engaging the lower end of said intermediate packing; a flange on said lower sleeve engaging the upper end of said lower packing; normally retracted slips disposed about said body; expander means engageable with the upper end of said upper packing and coacting with said slips for expanding them against the casing to resist upward movement of said upper packing in the casing; means on said body engageable with the lower end of said lower packing; sleeve means on said body extending between and engageable with said upper sleeve and the upper end of said intermediate packing; and a spacer sleeve on said body located between and engageable with said intermediate and lower sleeves.

18. In a well packer adapted to be lowered in a well casing: a tubular body having a port, said body comprising an upper section and a lower

section joined together by a detachable left-hand threaded connection; upper and lower normally retracted casing engaging packings surrounding said body and disposed on opposite sides of said port; normally retracted slips disposed around said body; expander means engageable with said upper packing and coacting with said slips for expanding them against said casing to resist upward movement of said upper packing in said casing; means on said body engageable with the lower packing for urging said lower packing upwardly upon upward movement of said body in the casing; means on said body between said packings for transmitting to said upper packing the upwardly directed force supplied by said body to said lower packing, in order to compress both packings and expand them against the well casing; and releasable lock means between said upper section and slips for selectively coupling said slips for longitudinal movement with said upper section or releasing said slips from said upper section to enable said body to move longitudinally with respect to said slips.

19. In a well packer adapted to be lowered in a well casing: a tubular body having a port; first and second normally retracted casing engaging packings surrounding said body and disposed on opposite sides of said port, each of said packings having an upper end and a lower end; first abutment means engageable with the well casing and with one of the ends of said first packing for resisting movement of said first packing in the casing; a first sleeve within said first packing and slideable on said body and within said first abutment means, said first sleeve having a flange engaging the other end of said first packing; second abutment means on said body engageable with one of the ends of said second packing; a second sleeve within said second packing and slideable on said body and within said second abutment, said second sleeve having a flange engaging the other end of said second packing; and means between said sleeves for transmitting to said first packing the force applied by said body to said second packing, in order to compress both packings and expand them against the well casing.

20. In a well packer adapted to be lowered in a well casing: a tubular body having a port; first and second normally retracted casing engaging packings surrounding said body and disposed on opposite sides of said port each of said packings having an upper end and a lower end; first abutment means engageable with the well casing and with one of the ends of said first packing for resisting movement of said first packing in the casing; a first sleeve within said first packing and slideable on said body and within said first abutment means, said first sleeve having a flange engaging the other end of said first packing; second abutment means on said body engageable with one of the ends of said second packing; a second sleeve within said second packing and slideable on said body and within said second abutment, said second sleeve having a flange engaging the other end of said second packing; means between said sleeves for transmitting to said first packing the force applied by said body to said second packing, in order to compress both packings and expand them against the well casing; and sealing means between each sleeve and said body to prevent fluid leakage therebetween.

21. In a well packer adapted to be lowered in a well casing: a tubular body having a port; upper and lower normally retracted casing engaging

packings surrounding said body and disposed on opposite sides of said port; upper abutment means engageable with the well casing and with the upper end of said upper packing for resisting movement of said upper packing in the casing; an upper sleeve within said upper packing and slidable on said body and within said upper abutment means, said upper sleeve having a flange engaging the lower end of said upper packing; lower abutment means on said body and engaging the lower end of said lower packing; a lower sleeve within said lower packing and slidable on said body and within said lower abutment means; said lower sleeve having a flange engaging the upper end of said lower packing; and means between said sleeves for transmitting force therebetween.

22. In a well packer adapted to be lowered in a well casing: a body; a sleeve slidable on the exterior of said body and having a flange; a normally retracted casing-engaging packing on said sleeve, said packing having one end engaging said flange; an abutment surrounding said body and slidable on said sleeve and engageable with the other end of said packing to expand said packing into engagement with the well casing; and sealing means engaging said sleeve and the exterior of said body to prevent fluid leakage therebetween.

23. In a well packer adapted to be lowered in a well casing: a tubular body having a port; a sleeve slidable on the exterior of said body below said port in close contacting leakproof relation with respect to said exterior of said body and having a flange, said sleeve having a skirt depending from said flange; a normally retracted casing-engaging packing on said skirt having its upper end engaging said flange; and an abutment fixed to said body and slidable on said skirt, said abutment being engageable with the lower end of said packing to expand said packing into engagement with the well casing.

24. In a well packer adapted to be lowered in a well casing: a tubular body having a port; a sleeve slidable on the exterior of said body below said port and having a flange, said sleeve having a

skirt depending from said flange; a normally retracted casing-engaging packing on said skirt having its upper end engaging said flange; an abutment fixed to said body and slidable on said skirt, said abutment being engageable with the lower end of said packing to expand said packing into engagement with the well casing; and sealing means engaging said sleeve and exterior of said body to prevent fluid leakage therebetween.

- 5 25. In a well packer adapted to be lowered in a well casing: a tubular member having a port; upper and lower normally retracted packings surrounding said body and disposed on opposite sides of said port; an upper abutment movable relatively of said body and engageable with the upper end of said upper packing; normally retracted slips disposed about said body; expander means engageable with said upper abutment and coacting with said slips for expanding them against the casing to resist upward movement of said upper abutment in the casing; an upper sleeve within said upper packing and slidable on said body and within said upper abutment, said sleeve having a flange engageable with the lower 10 end of said upper packing; a lower abutment mounted on said body and engaging the lower end of said lower packing; a lower sleeve within said lower packing and slidable on said body and within said lower abutment, said lower sleeve having a flange engageable with the upper end of said lower packing; and spacer means on said body disposed between and engaging said sleeves, in order that upward movement of said body can effect compression of both packings and their outward expansion against the well casing.
